BOOK STRUCTURE

Filed Nov. 18, 1929

UNITED STATES PATENT OFFICE

RAYMOND TRANE, OF OMAHA, NEBRASKA

BOOK STRUCTURE

Application filed November 18, 1929. Serial No. 408,051.

My invention relates to book structures and particularly to blank and note books employing sheets which are removable from and replaceable within the book-covers. It is the object of my invention to provide a notebook particularly adapted for use in schools and the like, where it is desirable to avoid or reduce to a minimum the production of noise, to avoid scratching and abrasion of desk-surfaces, and to promote health and sanitation by enabling the effective cleansing of the permanently used cover-portion of the book when the same becomes soiled. A further object of my invention is to provide, for loose-leaf notebooks, paper-retaining rings of non-metallic flexible material, and detachable means for connecting the ends of the ring-forming members, whereby the rings may be opened for the insertion or removal of the paper sheets at any portion of the pile or assemblage of sheets which constitute the filler of the book. A further object of my invention is to provide a book-cover and fastening means for paper sheets having perforations through which the fastening means extends to removably retain the sheets or leaves within the cover, wherein the book when opened will lie substantially flat upon a plane surface, with any desired number of the paper sheets at either side of the median line of the opened book.

In the accompanying drawings Fig. 1 is a transverse section of a book structure embodying my invention, the section being on the plane of the line 1—1 of Fig. 2, Fig. 2 is a plan view of the structure, with portions intermediate the ends broken away, Fig. 3 is a transverse section on the same plane as Fig. 1, but showing the central portion only of the book, in open position, and Fig. 4 is a detail section of one of the retaining-rings, on the plane of the line 4—4 of Fig. 2.

In carrying out my invention according to the illustrated embodiment thereof, I provide a book-cover comprising sides 10 and a back 11, formed integrally by molding the same from a flexible waterproof composition, such as rubber. At the marginal portions of the sides 10 are continuous external beads or reinforcing ridges 12, of greater thickness

than the central portions of the sides, said beads 12 being of substantially the same thickness as the back 11. Adjoining the back 11 the thickened reinforcing portions are extended to form semicircular bosses 14, best 55 shown in Fig. 2, through which are formed the openings 15 for the paper-retaining rings 16. Said rings are tubular and are of flexible and elastic material, such as rubber, each ring-forming member being a piece of elastic tubing shaped to assume normally a toroidal formation, with the ends slightly separated as shown by dotted lines in Fig. 4. The adjoining ends of the elastic annular tube are detachably connected by means of a short 60 plug or connector having bulbous ends or heads 17 of a diameter slightly greater than the inside diameter of the elastic tube, and having between the heads 17 a neck portion 65 of substantially the same diameter as the inside diameter of the elastic tube. When the heads 17 of the connector are forced into the ends of the elastic tube, the latter is slightly expanded to pass over the heads, but the ends contract to fit about the neck portion of the 70 connector, the end-surfaces abutting so that the tube forms a continuous ring, and each end-portion firmly gripping the respective head of the connector, so as to remain in engagement therewith unless the parts are forcibly pulled apart.

In connection with the described book-cover and retaining-rings I employ paper sheets 18 each having the usual perforations adjacent to one edge thereof for receiving the rings. The rings are opened, for insertion through the perforations of the paper sheets and the openings 15 of the cover, by pulling one end of each ring-forming tube from the respective head 17 of its connector. 85 For insertion or removal of one or more sheets at any portion of the pile or assemblage of sheets within the book, the book is opened as shown in Fig. 3, the sheets or leaves being separated at the place where the insertion or removal is to be made, the rings turned so that the joints thereof are between the separated groups of sheets, then the rings are opened, the insertion or removal of the 90 desired sheets effected, and the rings again 95 100

closed by reinserting the heads 17 of the connectors into the open ends of the ring-forming tubes.

By reason of the flexibility of the retaining-rings and book-cover, the same will lie substantially flat when the book is opened and laid upon a plane surface, as shown in Fig. 3, enabling the user to write upon any part of the sheets except the extreme inner portions which are perforated to receive the rings. When the book is closed it may be formed into a roll for convenience in carrying the same in the hand or pocket. Being of waterproof material, should the book-cover become soiled it may be readily and effectively cleansed by washing the soiled surfaces, and the same thus kept sanitary and attractive in appearance. The flexible and resilient rubber, or like composition, will reduce to a minimum the noise produced in a school or classroom by movement of notebooks or placing thereof upon desks by students using the same, and the surfaces of the desks or other furniture cannot be injured by sliding of the books across such surfaces. The flexible waterproof composition, being molded in an integral piece from the plastic raw material, and being undamaged by bending or rolling the same, is of great durability, and may be produced in colors or with surface designs such as to present a highly ornamental or attractive appearance.

Now, having described my invention, what I claim and desire to secure by Letters Patent is:

1. In a book structure, a book-cover molded integrally from flexible waterproof material and having aligned openings in its opposite sides adjoining the back thereof, rings of flexible elastic material passing through said openings and adapted to traverse perforate sheets to retain the same within the cover, each of said rings comprising an integral annularly formed tube of the flexible elastic material, and a connector having bulbous heads detachably gripped within the end portions of the elastic ring-forming tube.

2. In a book structure of the class described, paper-retaining rings, each comprising an annularly formed tube of flexible elastic material and a connector comprising bulbous terminal heads and an intermediate neck portion, said bulbous terminal heads being detachably connected with the end portions of the annular tube by expanding the same over the heads and onto the neck portion of the connector.

3. In a book structure of the class described, a paper-retaining ring comprising a tube of elastic rubber having normally an annular formation, and a member for detachably connecting the ends of said tube, said connecting member having a reduced neck portion and a head of larger diameter than the normal inside diameter of the tube,

said head being detachably insertible in an end of the tube by expanding the same thereover and onto the reduced neck portion of the connecting member.

4. A loose leaf notebook, comprising marginally perforate sheets, side covers of flexible waterproof material having openings adapted to register with the perforations of the sheets, flexible rings extended through said perforations and the openings of the side covers, said rings each comprising an integral annular non-metallic flexible member having an elastic tubular end portion, and a connector carried at the opposite end and having a head detachably insertible in said elastic tubular end portion by expanding the same thereover.
